(57) **CLAIM**

The ornamental design for a gypsum, door installation, prying and rasping tool, as shown and described.

DESCRIPTION

FIG. 1 is a front perspective view of a gypsum, door installation, prying and rasping tool showing my new design;

FIG. 2 is a rear elevational view thereof;

FIG. 3 is a top plan view thereof;

FIG. 4 is a bottom plan view thereof;

FIG. 5 is a left end view thereof; and

FIG. 6 is a right end view thereof

FIG. 7 is a front perspective view of the second embodiment;

FIG. 8 is a rear elevational view thereof;

FIG. 9 is a top plan view thereof;

FIG. 10 is a bottom plan view thereof;

FIG. 11 is a left end view thereof; and

FIG. 12 is a right end view thereof

FIG. 13 is a front perspective view of the third embodiment;

FIG. 14 is a rear elevational view thereof;

FIG. 15 is a top plan view thereof;

FIG. 16 is a bottom plan view thereof;

FIG. 17 is a left end view thereof; and,

FIG. 18 is a right end view thereof.
